UNITED STATES PATENT OFFICE.

CHARLES W. ENGLEMAN, OF ABILENE, KANSAS.

FUSE.

Application filed May 4, 1925. Serial No. 27,909.

This invention relates to an improved fuse, of the kind adapted to be incorporated in an electric circuit, so that when there is an overload of current passed through the circuit, such as is the case under abnormal conditions, the fuse will interrupt the passage of the current, until the normal condition is resumed.

The purpose of the invention is to provide a fuse which is automatic in operation, thus obviating the necessity of renewing or refilling, as is essential with the ordinary tube and cap fuse.

More particularly, the invention has reference to a fuse, which embodies a current conductor, preferably mercury, which, under normal conditions spans the space between the usual terminals and serves to convey current from one to the other, the mercury being vaporized and otherwise affected, under a predetermined heat to momentarily break the circuit, but resuming its normal shape under normal conditions.

The particular construction employed for accomplishing this result will become apparent from the following description and drawing.

In the accompanying drawing, forming a part of this application, and in which like numerals are employed to designate like parts throughout the same:

Figure 1 is a central longitudinal section through a fuse constructed in accordance with this invention, showing one embodiment of the same.

Figure 2 is a like view, showing a different embodiment of the invention.

Attention is first directed to Figure 1, wherein a body of insulation material, preferably glass is shown. In this instance, the body is formulated to provide a central hollow ball 1, which is open at its bottom. Extending from the open bottom, on diametrically opposite sides are integral branches 2 and 3, which incline slightly downward and outward. It will be noted that these branches are bored to provide main passages 4 and 5 respectively and auxiliary passages 6 and 7 respectively. The auxiliary passages communicate at their outer ends with the main passages, the main passages being closed at their outer ends. The inner ends of the main passages open into the central opening 8, at the bottom of the ball 1. The

auxiliary passages communicate with small ducts 9, which, in turn, communicate with the chamber provided upon the interior of the ball. Fitted upon the opposite ends of the branches are caps 10 and 11 of electricity conducting material, these caps being provided with pins 12, serving as contacts. These contact pins extend into and have portions exposed in the main passages 4 and 5. As before stated, these passages are filled with mercury which serves as a conductor between the caps 10 and 11 through the medium of the contact pins 12. The caps, in practice, will be provided with appropriate terminals (not shown), by means of which customary conducting wires may be connected therewith.

Observing Figure 2 now, it will be seen that a somewhat larger hollow ball 13 is provided, there being a single stem depending from this ball, and this stem being formed with main and auxiliary passages 14 and 15 respectively, in which the mercury conductor is confined. The upper end of the stem projects into the interior of the chamber provided in the ball 13 as indicated at 16. The upper ends of the passages 14 and 15 communicate with the chamber through the extension. Also, a pair of diagonal ducts 17 afford means by which the fluid is returned to its normal position. Furthermore, a cap 18 is fitted on the lower end of the stem and provided with a contact pin 19, and a sleeve 20 surrounds the upper portion of the stem, being provided with an appropriate contact 21. As in the first instance, this sleeve and cap will be provided with appropriate terminals or binding posts (not shown).

In operation, it will be found that there is sufficient mercury contained in the passages to accommodate the normal amount of current. When the current becomes abnormal, it will act upon the mercury to heat and vaporize a portion thereof which will collect in the spherical air tight chamber. The subtraction thus made by this vaporization will reduce the mercury conductor to a state to render it insufficient to carry the current. In this way, the circuit will be temporarily broken. As the heat reduces the vaporized mercury will automatically return to its original state and flow back into and fill up the main passage to provide

an unbroken fluid conductor. Thus, the operation of the fuse will be automatic according to the condition of the circuit.

- The purposes of providing the auxiliary passages and the ducts which lead from these auxiliary passages to the hollow bore will now be discussed. In order to provide a re-loading fuse which will operate as quickly as possible, it must have a quick return for the mercury. Fuses of this type have a small carrying capacity in amperes for high voltage must have an auxiliary passage to let the hot gas out or the mercury would get gas or air bound and would not return in the tube or passage provided therefor for some length of time, if at all, therefore, the mercury could not properly function in again closing the circuit without these auxiliary passages.
- Furthermore when the arc is started by blowing of the fuse there is a flaming arc created in the fuse and the auxiliary passages carry enough vapor gas to hold the flaming arc as long as the load stays on, and therefore when the load is dropped, the flaming arc stops and then reloads the fuse at once by leaving the hot gases out through the ducts and auxiliary passages, thus effecting the re-loading of the fuse immediately.
- These auxiliary passages 6 and 7 and the ducts 9 form an air vent, and also a means for letting the hot gases escape to effect a quick reload.

It is believed that persons familiar with circuit makers and breakers and partic-

ularly with thermal devices will be able to obtain a clear understanding of this invention.

For this reason, a more lengthy description is thought unnecessary.

While the preferred embodiment of the invention has been shown and described, it is to be understood that minor changes coming within the field of invention claimed may be resorted to, if desired.

I claim:

A fuse of the class described comprising a hollow ball which is open at its bottom, a pair of branch pipes extending laterally from the bottom of the ball in opposite directions and being inclined slightly downwardly toward their outer ends, the inner opposed ends of the branch pipes communicating with the open portion of the hollow ball, caps fitted over the ends of the pipes, said pipes being adapted to contain a quantity of mercury, contacts carried by the caps and extending into the respective ends of the pipes, the mercury normally bridging said contacts, each of said branch pipes being provided with a longitudinally extending air passage which communicates with the outer end of the respective pipe, the hollow ball being provided with ducts which afford communication between the inner end of the air passages and the interior of the hollow ball.

In testimony whereof I affix by signature

CHARLES W. ENGLEMAN.
